INVENTOR

George H Parsons
BY *Frank M. Ashley*
ATTORNEY

UNITED STATES PATENT OFFICE.

GEORGE H. PARSONS, OF NEW YORK, N. Y.

MEANS FOR GENERATING SOUND.

Application filed February 17, 1922. Serial No. 537,264.

To all whom it may concern:

Be it known that GEORGE H. PARSONS, a citizen of the United States, and a resident of New York city, borough of Manhattan, in the county of New York and State of New York, has invented certain new and useful Improvements in Means for Generating Sound, of which the following is a specification.

10 This invention relates to a sound device for toys and the object thereof is to provide means for generating sound to imitate a baby's voice.

The device is intended for use with a doll, 15 in which it is placed and which when moved in a certain way causes the voice to be generated and say "ma-ma".

A further object of my invention is to provide means whereby the device may be adjusted to say the word ma-ma slowly or quickly, that is, to regulate the time interval between the syllables.

A further object is to provide a construction in which all the moving parts with the exception of the vibrating reed are open to view and adjustment when the casing is opened, no working parts being concealed within the bellows or resonating chamber, and therefore, easy of access to adjust or repair.

Referring to the drawings forming a part of this specification:

Figure 1 indicates a doll in which the device is used and showing its preferred location.

Figure 2 is a plan view of the construction located within the casing, the top of which is removed.

Figure 3 is a longitudinal sectional view.

40 Figure 4 is a cross sectional view on line 4-4 of Figure 3.

A, indicates a doll and B a casing made of cardboard or other suitable material and having a cover portion B' that is easily removable from the body portion thereof and in which is located a thin cloth B² which covers an opening B³ formed in the cover, to permit the sound waves produced by the device to flow freely from within the casing.

50 C, indicates a bellows of the hinged type, the hinge being formed at C'. The bottom plate C² of the bellows may be secured to the casing B by screws D-D respectively, or in any other suitable manner. Mounted on the top plate C³ of the bellows is a base

plate E of metal which is made sufficiently heavy to serve the function of a weight to compress the air in the bellows in its closing action and force same through the sound producing reed F, which is mounted in a 60 resonating chamber G which chamber is provided with an air inlet H from the bellows chamber H', and an outlet H² to the casing. The resonating chamber may be made of cardboard or tin or other suitable cheap material and may be secured to the top plate C³ by screws I or in any other suitable way.

Extending vertically and secured to the sides of the casing B is a stamped form of metal J which extends across the casing and through slots J-J' respectively formed therein, and the ends of which are bent downward on the outer side of the casing as illustrated at K-K respectively which serves to brace the casing while at the same 70 time the metal form is held in proper position to support its limbs L-L respectively, which extend downward therefrom and extend under the end of the bottom plate C⁴ of the bellows and is firmly held thereby. 80

A slot M is formed in each of said limbs L through which extend pins N-N respectively which in turn carries slideable bars O-O respectively which are vertically adjustable relatively, and are held in their adjusted relation by the thumb screws or nuts P-P which connect with the pins N-N respectively.

These pins O-O are made of flexible yielding material, such as soft rubber or 90 thin strips of celluloid, which can be easily bent by pressing down the projecting end but which will instantly resume its horizontal position when the pressure is removed.

95 One of said pins O may be made more flexible and easier to bend than the other by being made of smaller diameter relatively or it may be shorter in length to serve the function hereinafter described.

P indicates a stiff wire which carries a valve P' which controls the opening H² in the resonating chamber. The wire P is connected to a short cylinder Q, which is mounted on a shaft Q', which in turn is held by two brackets R-R respectively and a spring S is connected to said cube 2 at one end and to the plate E at its opposite end. The end P² of the wire P projects beyond the limbs L-L respectively and is adapted to con- 100 105 110

tact with the flexible members O—O. A U shaped frame F is also connected to the plate E at its two extremities and its upper portion extends above the wire P and serves 5 to limit the upward movements of the valve P' relative to the opening H² formed in the resonating chamber. A small vent opening indicated by V is located in the resonating chamber to permit air to escape therefrom 10 during the period that the valve P' closes the opening H² so that the reed F can continue to vibrate when this valve is closed.

The device operates as follows:—With the bellows closed as illustrated in Figure 3, 15 the first operation is to turn the casing B so that the cover side B' is below the bottom of the casing, when the bellows will be expanded by reason of the weighted plate E and parts mounted thereon, causing the 20 parts to assume the position illustrated in the dotted lines in Figure 3 in which position the end of the wire P² will have reached a position adjacent the top bar J and the bellows in its opening movements will have 25 become filled with air.

When the casing is again turned to its normal position as illustrated in Figure 4, the bellows will start to close and will be compressed by the weight E causing the air 30 to flow from the bellows chamber H' through the passages H and H' to the vibrating reed F and causing same to vibrate to produce sound which is amplified by the resonating chamber G.

35 In the commencement of this operation, the bellows in its downward movements carries the end P² of the wire in contact with the upper flexible member O, which first causes the valve P' to close the opening H² in the resonating chamber and as the bellows continues its closing movement, sound 40 is emitted by the vibrating reed F which escapes through the opening V to produce a slight murmuring note and as the bellows 45 continues to descend the flexible member O is bent until the end P² of the wire slips past, when instantly, the spring S acts to lift the valve P', thus opening the passage H² and the loud volume of sound is at once 50 emitted causing the first syllable of the word "ma-ma" to be uttered and as the bellows further closes the end P² comes in contact with the lower element O, which first closes the valve P' and bends in the same manner 55 as the upper one did but by reason of its greater length, the end P² is retarded for a greater length of time in passing this pin than in passing the upper one and, therefore, 60 the sound syllable of the word is spoken in a slower period of time.

By reversing the length of the two pins relatively, the reverse action in speaking the word would be effected.

65 By changing the relative distance between the two flexible members O—O respectively,

the period of time in which the word is uttered would be decreased and vice-versa, as will be readily understood.

Having thus described my invention, I claim as new:—

70 1. A sound generating device comprising a casing having an air compressing device therein, a sounding device operated thereby, a resonating chamber, a valve controlling the rate of flow from said resonating chamber and means comprising a plurality of resilient members adapted to automatically close said valve, and means for opening same in relatively quick time compared to the closing movement, when said resilient members release said valve.

75 2. A sound generating device comprising a casing having an air compressing device therein, a sounding device operated thereby, a resonating chamber, a valve controlling the rate of flow from said resonating chamber, and means comprising a plurality of resilient members adapted to automatically close said valve, and open same in relatively quick time compared to the closing movement and means for regulating the time period between the first and second opening 80 of the valve.

85 3. A sound generating device comprising a casing having an air compressing device therein, a sounding device operated thereby, a resonating chamber, a valve controlling the rate of flow from said resonating chamber and means comprising a plurality of resilient members adapted to automatically 95 close said valve, and open same in relatively quick time compared to the closing movement and means for regulating the time period of the closing movement of the valve.

100 4. A sound generating device comprising a casing having an air compressing device therein, a sounding device operated thereby, a resonating chamber, a valve controlling the rate of flow from said resonating chamber, a rod on which said valve is mounted, means comprising a resilient member which is adapted to operate said rod to close said valve and means for regulating the position 105 of said resilient member.

110 5. A sound generating device comprising a casing having an air compressing device therein, a sounding device operated thereby, a resonating chamber, a valve controlling the rate of flow from said resonating chamber, a rod on which said valve is mounted, means comprising resilient members which are adapted to operate said rod to close said valve and means for regulating the position 115 of said resilient members.

120 6. A sound generating device comprising a casing having a gravity actuated air compressing device therein, a sounding device carried by said air compressing device, a valve controlling the flow of air from said 125

sounding device, said valve being adapted to be moved with said air compressing device, a resilient finger for engaging said valve during its movement to close the same and 5 spring means for opening the same when said said valve passes out of engagement with said resilient member.

7. A sound generating device comprising a casing having a gravity actuated air compressing device therein, a sounding device carried by said air compressing device, a 10 valve controlling the flow of air from said sounding device, said valve being adapted

to move with said air compressing device, means for engaging said valve during its 15 movement to close the same and means for substantially instantaneously opening the same when said valve passes out of engagement with said first mentioned means.

Signed at New York, in the county of New 20 York and State of New York, this 3rd day of February, A. D. 1922.

GEORGE H. PARSONS.

Witness:

FRANK M. ASHLEY.
